UNITED STATES PATENT OFFICE.

CHARLES A. YOUNG AND GEORGE A. YOUNG, OF DETROIT, MICHIGAN.

EXHAUST-HEAD FOR STEAM-PIPES.

SPECIFICATION forming part of Letters Patent No. 668,866, dated February 26, 1901.

Application filed June 7, 1900. Serial No. 19,855. (No model.)

To all whom it may concern:

Be it known that we, CHARLES A. YOUNG and GEORGE A. YOUNG, subjects of the Queen of Great Britain, residing at Detroit, county 5 of Wayne, State of Michigan, have invented a certain new and useful Improvement in Exhaust-Heads for Steam-Pipes; and we declare the following to be a full, clear, and exact description of the invention, such as will enable 10 others skilled in the art to which it appertains to make and use the same, reference being had to the accompanying drawings, which form a part of this specification.

Our invention has for its object the construction of an improved exhaust-head for steam-pipes of superior construction and utility; and it consists of the combination and arrangement of devices hereinafter described and claimed, and illustrated in the accompanying drawings, in which—

Figure 1 is an exterior view in perspective. Fig. 2 is a vertical section thereof. Fig. 3 is a horizontal section on the line 3 3, Fig. 2.

Our invention is particularly designed to 25 separate oil and other matters from the steam, to condense the steam, to prevent the discharge of any annoying or injurious spray from the head, our invention making provision not only for separation and condensation 30 in the exhaust-head, but also for carrying away the condensation and matters separated from the steam and preventing its discharge from the top of the exhaust-head.

Our invention aims to provide a large condensing-surface to prevent any noise or back pressure.

Our invention is especially adapted for use in connection with high-speed engines.

We carry out our invention as follows:

As shown in the drawings, the exhaust-head is made with an outer jacket, (indicated at *a*.) which may be made of heavy galvanized iron or of any other suitable material. The jacket is provided with an inlet-pipe *b*, to be 40 connected in any suitable manner with the steam-pipe, suitable connections being shown at *c* to engage the head with the steam-pipe. Within the jacket *a* is a drum or cylinder *d*, having at its lower end a series of baffle-plates, (indicated at *e*.) openings *f* being provided 45 between said plates. Within the row of baffle-plates *e* is an additional series of baffle-

plates *g*, openings *h* being provided therebetween. The series of baffle-plates *g* and the series of baffle-plates *e* are staggered the one 55 relative to the other. The inner baffle-plates *g* depend from a deflector *i* within the drum or cylinder *d*, said deflector having its apex projecting downward, as shown, the deflector being provided near the apex with a discharge- 60 pipe *j*, leading therefrom. The drip from the discharge-pipe and from the various series of baffle-plates is caught at the lower end of the jacket, the lower end *k* of the jacket being 65 cone-shaped, converging downward about the connecting-pipe *b*, and provided with a discharge-opening (indicated at *l*) communicating with a waste-pipe *m*. The upper end of the jacket is provided with a deflecting-cap *n*, provided with a discharge-opening *p* 70 at the center thereof, the center of the cap being provided with a discharge-pipe *q*, projecting downward inside the upper end of the cylinder *d*, the lower end of the discharge-pipe being provided with a gutter, (indicated 75 at *r*.) The gutter is provided with one or more discharge-pipes *s*, which may converge to discharge upon the deflector *i* or into proximity with the pipe *j*. The connecting-pipe *b* carries the entering steam upward within 80 the inner row of baffle-plates *g*. It will be evident that partial separation will be made by the inner row of baffle-plates, oil and other substances adhering to the surfaces of said plates. The outer row or series of baffle- 85 plates will likewise effect additional separation of matters contained in the exhaust-steam, the same passing between the staggered baffle-plates through the openings *h* and *f*. The drip from the baffle-plates, as 90 already indicated, is collected in the lower end of the jacket. The steam passes through the outer openings *f* between the outer series of baffle-plates, passing upward about the surface of the cylinder *d*, the same being carried 95 down over the upper end of said cylinder and under and into the lower end of the cylinder or pipe *q*. The steam condensed on the surfaces of the pipe *q* is caught in the gutter *r* and carried by the pipes *s* upon the deflector *i*. 100 So, likewise, the steam condensed on the inner surface of the cylinder *d* at its upper end will be carried by said deflector to the discharge-pipe *j*. In this manner all drip is

caught and prevented from being blown out through the pipe *q*. All the drip from the steam is thus carried to the discharge-pipe *l* and to the waste-pipe *m*. By making the

5 diameter of the pipe *q* larger than the diameter of the pipe *b* it will be obvious that back pressure is entirely avoided and also noise. After leaving the pipe *b* it will be obvious that the steam passing between the staggered 10 rows of baffle-plates and thence to the upper pipe *q*, between the jacket or shell and the inner cylinder *d*, and downward toward the deflector *i*, between the cylinder *d* and the pipe *q*, comes into contact with a large separating 15 and condensing surface, the final separation taking place at the gutter *r*.

By this construction any annoying and destructive spray is prevented from being discharged from the exhaust-head. The cap *n*, 20 deflecting downward, carries all the drip which may be condensed thereupon to the pipe *q*, and thence to the gutter *r*, said gutter thus collecting all the drip from the cap *n* and outlet-pipe *q*.

25 What we claim as our invention is—

1. In an exhaust-head provided with a cap at its upper end, the combination with a jacket, of an inlet-pipe, a waste-pipe, an interior cylinder, an outlet-pipe leading through 30 said cap having its lower end extending into the interior of the cylinder and provided with a gutter, a deflector within said cylinder below the outlet-pipe, discharge-pipes leading from said gutter and from said deflector, and 35 separating devices located below said deflector, substantially as described.

2. In an exhaust-head, the combination with a jacket provided with a cap at its upper end, of an inlet-pipe, a waste-pipe, an interior cylinder, an outlet-pipe leading through 40 the upper end of the jacket provided with a gutter at its lower end to receive the condensation from the surface of the cap and from the outlet-pipe, a deflector within said cylinder below the outlet-pipe, discharge-pipes leading from said gutter and said deflector, and baffle-plates located below said deflector.

3. In an exhaust-head, the combination with a jacket provided with an inlet-pipe and 45 with a waste-pipe, of an interior cylinder, an outlet-pipe leading through the upper end of the jacket provided with a gutter at its lower end, a deflector within said cylinder below the outlet-pipe, discharge-pipes leading from 50 said gutter and from said deflector, and two

rows of baffle-plates the one within the other below said deflector, the baffle-plates of the two rows staggered the one relative to the other.

4. In an exhaust-head, the combination 60 with a jacket provided with an inlet-pipe and with a waste-pipe, of an interior cylinder, a deflector within said cylinder provided with a discharge-pipe, an outlet-pipe leading through the top of said jacket provided with 65 a gutter at its lower end, a discharge-pipe leading from said gutter to discharge through the pipe leading from the deflector, and separating devices located below said deflector, said jacket provided with a cap at the upper 70 end surrounding the upper end of the outlet-pipe.

5. In an exhaust-head, the combination 75 of a jacket provided with an inlet-pipe at its lower end and with a waste-pipe, of an interior cylinder, a deflector within said cylinder provided with a discharge-pipe, a row of baffle-plates at the lower end of the cylinder, an additional row of baffle-plates within the first-named row, and an outlet-pipe at the upper 80 end of the head provided with a gutter, and with an outlet-pipe leading from the gutter to discharge through the pipe leading from the deflector, the lower end of the jacket being cone-shaped.

6. In an exhaust-head, the combination 85 of a jacket provided with a cap at its upper end, and with a cone-shaped lower extremity having a waste-pipe leading therefrom, an inlet-pipe leading into the lower end of the 90 head, a cylinder within the jacket provided with baffle-plates at its lower end and with openings between said baffle-plates, a deflector within said cylinder, an additional series 95 of baffle-plates beneath the deflector provided with openings therebetween, an outlet-pipe leading through said cap and projecting downward within the upper end of the cylinder provided with a gutter at its lower extremity, and discharge-pipes leading from the gutter 100 and from the deflector to discharge the drip through said waste-pipe, the two rows of baffle-plates being staggered.

In testimony whereof we sign this specification in the presence of two witnesses.
